CAN HANGER

Earl J. Carroll, Tarrytown, N.Y.

Application June 2, 1954, Serial No. 434,001

1 Claim. (Cl. 248—311)

This invention relates to a hanger for removably supporting cans of the type widely used for canning beer, fruit juices, vegetables and other food products.

The hanger in which the present invention is embodied is adapted to be secured to a wall or other supporting surface and provides an unobtrusive and convenient means by which such containers can be supported securely but from which the containers can be removed readily when desired.

Various types of supports for such cans have been devised and some of the many forms have found commercial application. However, these earlier supports have had shortcomings that limited their use. For example, some of the supports have been too large in that they require excessive wall space or protrude too far into the room. Other types require too much manipulation to secure the cans in position or to release them. Some of the supports are not reliable enough and do not hold the cans firmly enough. Moreover, some of the proposed arrangements are so expensive they cannot be used for many applications requiring low cost hangers.

The present invention is described as embodied in a hanger not much larger in area than a postage stamp and which may project from the supporting surface no more than one-eighth or three-sixteenths of an inch. Such a hanger provides a secure support for ordinary size beer and food cans and the cans can be placed in or lifted out of the hanger quickly and easily. In addition the hanger is simple in construction and can be readily manufactured by inexpensive high-speed operations so that the cost of the hanger is low enough that it can be used in the greatest number of different applications.

Such hangers are useful, for example, for holding tins of food, oil, beer and other products for display purposes; for storage in the home by making use of wall space that would otherwise be wasted; and for supporting cans in vehicles such as cars, trailers, boats, etc. In such applications each can is visible so that any container can be selected readily from an assortment.

Hangers embodying the present invention are particularly useful in applications where it is important that the cans be held securely yet instantly releasable without the application of significant force. For example, fire-extinguishing products are sometimes packaged in cans having an exterior chime at one end. Such fire extinguishers are advantageously supported by hangers embodying the present invention so that they are in no danger of being dislodged accidentally yet are ready for instant use in any emergency.

The construction of a simple and inexpensive can hanger embodying the invention will be made clear from the following description considered in connection with the accompanying drawings, in which:

Figure 1 is a partial perspective view of a can supported by a hanger embodying the invention;

Figure 2 is an enlarged perspective view of the hanger shown in Figure 1; and

Figure 3 is an enlarged partial sectional view taken vertically through the center of the hanger.

As best shown in Figure 2, the hanger is formed from a single sheet of metal, such as aluminum or steel, and 5 has a planar base or supporting portion 2 from which extend two side flanges 4 and 6 formed by bending the side edge portions of the base 2 forwardly at right angles to the plane of the base.

A top flange 8 is formed by bending the upper edge 10 of the base 2 forwardly and supports a narrower downwardly-extending lip 10 that engages the inner surface 15 of the chime or rim of the can that is to be supported.

Two chime-receiving notches 12 and 14 are formed in the upper forward edges of the side flanges 4 and 6 adjacent the top flange 8. The corners of these notches, indicated respectively at 12a and 14a, are smoothly rounded so that the surfaces of the notches will conform nicely to the outer surface of the chime on the conventional can. The outer edges of the top flange 8 preferably 20 project slightly over the upper ends of the notches 12 and 14 but this is not essential to the construction. In order to allow for the curvature of the rim 22, the width of the flange 8 is reduced on either side of the lip 10, as indicated at 15. The base 2 has a key-hole shaped 25 opening 16 so that the hanger can be secured conveniently to a wall or other supporting surface, for example, by a screw 18.

In use, after the hanger is fastened to a wall or other support, a can 20 is positioned as shown in Figure 1 with 30 its upper rim 22 extending through the notches 12 and 14 and behind the lip 10. The outer edges of the side flanges 4 and 6 engage the outer surface of the can 20 below the rim 22.

The can 20 is positioned in the hanger by tilting the 35 can forwardly, as indicated by the broken line 20a in Figure 3, and inserting the rim 22 under the lip 10. The can is then straightened up to the position shown in Figure 1 where it is securely supported by the hanger. To remove the can, the lower part of the can is pulled outwardly until the lower edge of the rim 22 is free of the 40 notches 12 and 14.

From the foregoing description it will be apparent that the can hanger embodying this invention is well adapted to fulfill the ends and objects set forth above and that it 45 can be manufactured in quantity by conventional construction techniques at a cost so low that it has the widest possible application.

It will be clear that various modifications can be made in the construction set forth herein to enable the invention to be best adapted to each particular use or circumstance of construction. For example, although metal construction has been illustrated, the hanger can be formed of plastic or other material so long as the material can be readily fabricated and has the necessary 55 strength.

I claim:

A metal bracket for attachment to an upright surface for removably supporting, in a position substantially parallel to such surface, a can of the type having an outwardly protruding chime extending along one end of a side wall; said bracket including an upwardly extending substantially flat base constructed for securing to the upright surface and having upwardly extending side flanges projecting forwardly from its side edges, and substantially coextensive with the side edges and substantially normal to the base; the outer edges of said flanges being substantially parallel to said base; said flanges having forwardly and upwardly opening notches at the upper ends of their outer edges, the depth of said notches laterally of the flanges being substantially less than the width of said flanges; and a retaining lip of substantial lateral extent extending forwardly from the upper edge of said

base a distance of the order of the width of said flanges and then downwardly toward the plane of the bottom edges of said notches and terminating short of such plane; said lip being adapted to extend over the chime of a can when supported in said notches and to engage substantially widely circumferentially spaced portions of the inner surface of the chime of a can so supported to restrict movement thereof out of said notches; the side wall of a can, when a can is supported in said notches, engaging the entire length of the outer edges of said flanges, to inhibit oscillation of the can so supported, and the bracket being adapted to support a can entirely outwardly of the outer surface of said base; the lower edge of said lip, due to its substantial length, limiting the oscillation of a

15

can supported in said notches, by engagement with a closed end wall of such can.
